UNITED STATES PATENT OFFICE.

JAMES R. IRWIN, OF SAN FRANCISCO, CALIFORNIA.

BOAT-DAVIT.

1,304,984.

Specification of Letters Patent. Patented May 27, 1919.

Application filed August 15, 1918. Serial No. 249,936.

To all whom it may concern:

Be it known that I, JAMES R. IRWIN, a citizen of the United States, residing at the city and county of San Francisco and State of California, have invented new and useful Improvements in Boat-Davits, of which the following is a specification.

This invention relates to ship construction, and particularly pertains to boat davits 10 therefor.

When a life boat is lowered from a ship, it often happens that the lowering tackle is not fed out from both ends of the boat uniformly and that the boat is upturned with disastrous results. It is the principal object of this invention to provide a simple means for supporting a life boat upon the deck of a ship and permitting the boat to be raised or lowered without danger of tipping 20 and with minimum manual exertion as compared to that required in handling boats suspended from davits of present day construction.

The present invention contemplates the use of a pair of rigid uprights to which are pivoted swinging arms adapted to be simultaneously actuated by a mechanism which will cause the two members to swing outwardly or inwardly in unison and to carry a 30 tackle from which the opposite ends of a life boat are dependent, said tackle being provided with winding means which will uniformly tighten and release both tackle ropes at once.

35 The invention is illustrated by way of example in the accompanying drawings, in which—

Figure 1 is a view in side elevation, disclosing a life boat as operatively connected 40 to the davits.

Fig. 2 is a view in end elevation, illustrating the davits and the manner in which a life boat is handled, said view further indicating in dotted lines the outer position of 45 the boat.

Referring to the drawings, 10 indicates the deck of a ship upon which are secured upright beams 11 and 12. These beams are parallel to each other and are bolted to the deck by bolts and angle plates 13. As here shown, the beams are of channel section and provide runways upon their opposite sides for a vertically moving carriage 14.

The carriage 14 is composed of separate 55 plates 15 and 16 which extend along opposite faces of the beam and are secured to-

gether by corner pins 17. These pins space the two plates in relation to each other and also form axles for rollers 18. The rollers are arranged in pairs along the inner and outer faces of the beam and are adapted to roll therealong. The carriages are fitted with threaded lugs 19 through which vertically extending screws 20 are positioned. These screws are journaled to the beam 65 within brackets 21 and 22 secured at their opposite ends. The lower end of each screw is fitted with a gear 23 in mesh with gears 24. These last named gears are fixed upon a horizontally extending operating shaft 25. 70 This shaft is also journaled in the standards 11 and 12 and may be rotated by cranks 26 and 27 fixed to the opposite ends of the shaft. By this means two persons may rotate the shaft and exert sufficient power to raise the 75 boat from the water, if desired.

Intermediate the length of the shaft is a worm gear 28, which is in mesh with a worm wheel 29 carried by bearing standards 30. These standards are fixed to the floor of the 80 deck and rotatably support the worm wheel 29 as it is operated by a crank arm 31. By this mechanism the shaft 25 may be operated by a single man, if desired. The standards 30 may also be formed with upwardly extending brackets 32 through which the shaft 85 25 extends and by which it is stabilized.

Extending through the plates of each carriage 14 is a pivot pin 33 which forms a connection for links 34. The upper ends of 90 these links are pivoted by pins 35 to swinging booms 36 which are in alignment with the standards of the davits and are secured by bottom pins 37 within brackets 38 fixed upon the deck. These members are adapted 95 to swing through a vertical plane and are fitted at their free ends with brackets 39 forming a pivotal support for sheave blocks 40. The sheave blocks may be of any desired construction and accommodate hoisting cables 41 which are led over idler pulleys 41' rotatably secured to the upper ends 100 of the standards 11 and 12. The lower run of each cable is fitted with a block 42, to which is connected a locking and releasing 105 hook 43. This hook is constructed substantially as disclosed in my issued patent entitled "Locking and releasing device," No. 1,242,809, dated October 9th, 1917, and as there set forth it automatically releases the 110 opposite ends of the boat simultaneously, thus preventing a premature releasing at

either end of the boat which would possibly overturn it.

The cables 41 are led to a single drum 47 which is secured to the deck of the ship and 5 is adapted to be rotated by complementary gears 48 which are driven by rotation of spiral gears 49. These last named gears are carried by a standard 50 and actuated by 10 crank arm 51. One of the cables is led onto the drum from one side and the other cable from the opposite side, so that rotating the drum in either direction will simultaneously wind or unwind the cables.

The life boat is supported upon blocks 15 44 and 45 which are secured to the deck of the vessel and are especially shaped to conform to the hull of the life boat and to accommodate the keel thereof without permitting the boat to rock. Each of these blocks is 20 formed in two parts; the outer part being fastened to the deck by a hinge 46 which will permit it to swing downwardly on to the deck and to afford clearance for the boat, so that it may swing directly outwardly from 25 the side of the ship without the necessity of being raised. The two portions of each block are secured in their normal upright positions by locking rods 46 which extend through openings in the two blocks and 30 hold them against movement.

In operation, the life boat is positioned upon the deck of the ship, as shown in Fig. 2. In the event that it is to be lowered the locking shafts 46 are withdrawn from their 35 apertures to permit the outer portions of the blocks 44 and 45 to swing longitudinally of the life boat and to assume positions flat upon the deck of the ship. When this has been accomplished the shaft 25 may be rotated 40 by the crank 31 or the cranks 26 and 27 and it will be evident that power may be applied to all three cranks. This will produce a simultaneous rotation of the two shafts 20 and will cause the carriages 14 to 45 move upwardly along the standards 11 and 12, as indicated by dotted lines in Fig. 2. As this carriage pursues its upward course of travel the lower ends of the links 34 will be raised and will force the outer ends of 50 these links outwardly. This will tend to swing the booms 36 upon their pivots 37 and cause them to swing outwardly to overhang the side of the ship.

After the life boat has been swung clear 55 of the ship the drum 47 may be rotated to pay out the hoisting cable and thus allow the boat to be lowered to the surface of the water. When a desired point has been reached in the travel of the boat the hooks 60 43, at the opposite ends thereof, may be simultaneously actuated to disengage the blocks 42 and will permit the boat to swing free of the hoisting tackles.

It will be noted that due to the fact that 65 the carriages 14 are directly supported upon

the upright beams 11 and 12, there will be no tendency for the threaded lugs 19 to bind upon the screws 20 and thus the apparatus may be easily operated without excessive wear and without the possibility of causing 70 difficulty when the davits are to be used.

It will be readily recognized that in case the boat is to be raised a reverse operation will easily elevate the boat and swing it in over the sides of the ship to thereafter assume a position of rest upon the blocks 44 and 45.

It will thus be seen that the form of boom here disclosed embodies simple and powerful means for facilitating in its manipulation 80 and, further, provides means whereby two or more davits may be simultaneously actuated by mechanism manually operated by one or more persons. It will also be noted that the means for actuating the tackle mechanism 85 will insure speed and certainty in operation and cause the boat to be handled with safety.

Having thus described my invention, what I claim and desire to secure by Letters Patent is:—

1. In a device of the character described, a fixed vertical beam, a boom pivoted at the lower end of said beam and swinging in the same plane therewith, a carriage through which the beam extends, anti-friction members interposed between the carriage and the opposite sides of the beam for facilitating in the movement of the carriage therewith, a rigid link member pivoted at its outer end to the boom and at its 100 inner end to the carriage and means for changing the relative positions of the carriage along said beam and thereby affecting the link to change the angular position of the boom.

2. In a device of the character described, a rigid vertical beam, a carriage through which said beam extends and movable therewith, a plurality of rollers along the opposite sides of the beam and carried by the carriage for the direct support thereof, a boom adapted to swing from a pivot at the foot of the beam and in the same plane therewith, a rigid link pivoted near the outer end of the boom and pivotally secured by its opposite end to the carriage and a screw member extending vertically as supported by the beam and adapted to raise and lower the carriage.

3. Boat davits comprising vertical standards, vertically swinging booms pivoted at the foot of each standard, carriages mounted upon each of said beams for slidable vertical movement therewith, sets of rollers rotatably supported by the carriage and disposed to bear against the opposite sides of the standards, rigid links pivoted to the carriage by their one ends and pivoted to the outer ends of the booms by their other ends, screw means for simultaneously rais- 120 125 130

ing or lowering the carriages, block and tackle mechanism dependent from the outer end of the booms, and means for simultaneously operating said tackle.

5 4. Boat davits comprising vertical standards, vertically swinging booms pivoted at the foot of each standard, carriages mounted upon each of said standards for slideable vertical movement therealong, sets of rollers rotatably supported by the carriage and disposed to bear against the opposite sides of the standards, rigid links, each link pivoted to the carriage by one end and pivoted to the outer end of its boom by the other 15 end, screw means for simultaneously raising or lowering the carriages, block and tackle mechanism dependent from the outer end of the booms, means for simultaneously operating said tackle, blocks alongside the 20 boom adapted to normally support a boat connected with the tackle, and means incorporated therein, whereby the boat may swing free of the blocks when the boom is swung outwardly and without the manipulation of the tackle.

5. In a device of the character described, a rigid vertical standard, a carriage carried and mounted thereon, comprising side plates disposed along the opposite sides of 30 the standard, a plurality of rollers carried by the side plates and disposed along the opposite edges of the standards, a vertically swinging boom pivoted at the foot of said standard and swinging in the same plane 35 therewith, a rigid link pivoted by its outer end to the free end of the boom and by its inner end to the plates of the carriage, a threaded lug extending outwardly from one plate of the carriage, an elevating screw 40 parallel to the standard and rotatably supported by its opposite ends thereon, and means for operating said screw.

6. In a device of the character described, a pair of davit units each comprising a 45 rigid vertical standard, a carriage carried and mounted thereon, comprising side plates disposed along the opposite sides of the standard, a plurality of rollers carried

by the side plates and disposed along the opposite edges of the standards, a vertically 50 swinging boom pivoted at the foot of said standard and swinging in the same plane therewith, a rigid link pivoted by its outer end to the free end of the boom and by its inner end to the plates of the carriage, a 55 threaded lug extending outwardly from one plate of the carriage, an elevating screw parallel to the standard and rotatably supported by its opposite ends thereon, a horizontal shaft journaled by its opposite ends 60 through the two standards, gearing connecting said shaft with the elevating screws and irreversible gearing by which the shaft may be rotated.

7. In a device of the character described, 65 a pair of davit units each comprising a rigid vertical standard, a carriage carried and mounted thereon, comprising side plates disposed along the opposite sides of the standard, a plurality of rollers carried 70 by the side plates and disposed along the opposite edges of the standards, a vertically swinging boom pivoted at the foot of said standard and swinging in the same plane 75 therewith, a rigid link pivoted by its outer end to the free end of the boom and by its inner end to the plates of the carriage, a threaded lug extending outwardly from one plate of the carriage, an elevating screw 80 parallel to the standard and rotatably supported by its opposite ends thereon, a horizontal shaft journaled by its opposite ends through the two standards, gearing connecting said shaft with the elevating screws 85 and a worm gear carried on the shaft, a complementary worm member in mesh therewith and a crank by which said complementary worm may be operated to rotate the shaft.

In testimony whereof I have hereunto set 90 my hand in the presence of two subscribing witnesses.

JAMES R. IRWIN.
